UNITED STATES PATENT OFFICE.

JOHN R. MARSHALL, OF MCKEAN, PENNSYLVANIA.

ELECTRIC SWITCH.

Application filed June 5, 1925. Serial No. 35,094.

This invention is designed to provide an out-door switch for electric wires, or conduits, the purpose of the switch ordinarily being to break the connection when it is 5 desired to make repairs or for other purposes rather than for normal use. In carrying out the invention I prefer to connect the ends of the wires so that these ends are properly insulated when the switch is open 10 but will not break the mechanical connection of the conductor. Features and details of the invention will appear from the specification and claims.

The invention is illustrated in the accompanying drawings as follows:—

Fig. 1 shows a perspective view of the device.

Fig. 2 a central vertical section of the device.

20 Fig. 3 a plan view of the switch plate. 1—1 marks the conductors. These conductors terminate in loops 2 which are secured on posts 3—3. The posts are embedded in insulating blocks 4 which may be of 25 glass porcelain, or similar material.

The insulating block is inclined from a central peak so as to readily shed water and prevent the bridging of the conductors through a water connection and is provided 30 with an annular groove 5 in which is arranged a re-enforcing wire 6. The block is also provided with vertical openings 7 and the wire as it is carried from the loop is swung over the conductor at 8 and the end 35 drawn through the opening 7 and returned and wound at 9 on the conductor. It will be seen, therefore, that the wire loop formed through the opening 7 prevents a falling of the conductor wires with any breakage or 40 damage to the post or breaking of the insulating block because the re-enforcing wire 6 forms a complete annulus through the loops formed in the wire through the openings 7 and consequently forms a continuous 45 wire linkage.

A switch plate 10 has a perforation 11 which is mounted on one post and a slot 12 which engages the other post. Metallic

nuts 13 are screwed on the post and clamp the switch plate 10 on the loops 2 of the 50 conductor wires, the clamping washers 14 being provided at the top of the insulating block to receive the thrust. I prefer to cover the nuts 13 with an insulating shell 15 such as rubber so that they may be more 55 safely handled in opening or closing the switch. When it is desired to open the switch the nuts 13 are loosened and the plate 10 swung clear. The nut at the pivot may then be slightly tightened so as to prevent 60 the accidental closing of the switch.

In order to prevent a bridging across of water should the conductors be slightly inclined I preferably provide a cross groove 65 16 on the underside of the insulating block 65 which forms a drip edge and prevents the continuous flow of water across the bottom.

What I claim as new is:—

1. In an electric switch, the combination of an insulating block having perforations 70 therethrough and a surrounding re-enforcing wire; conductors looped through the perforations and insulated from the surrounding wire said conductors supporting the block; and a switch plate detachably 75 connecting said conductors.

2. In an electric switch, the combination of two conductor posts; an insulating base in which the posts are mounted; conductors leading to the posts and supporting the 80 base; a surrounding re-enforcing wire on the insulating base insulated from the conductors; and a conductor switch plate between the posts and detachable from one of the posts.

3. In an electric switch, the combination of an insulating block; conductors leading to each end of the block; and a switch connection between the conductors, the insulating block being inclined at its top with a 90 peak between the conductors and having a drip groove in its bottom surface opposite to and in line with the peak.

In testimony whereof I have hereunto set my hand.

JOHN R. MARSHALL.
